United States Patent Office

Des. 195,476
Patented June 18, 1963

195,476

BEVERAGE CADDY

Kurt E. Christoffersen, Gales Ferry, Conn., assignor to Artistic Wire Products Co. of Conn., Incorporated,
Norwich, Conn., a corporation of Connecticut

Filed Mar. 27, 1962, Ser. No. 69,451

Term of patent 14 years

(Cl. D44—10)

FIG. 1 is a top plan view of a beverage caddy embodying my new design.

FIG. 2 is an elevational side view of said beverage caddy.

FIG. 3 is an elevational end view thereof.

I claim:

The ornamental design for a beverage caddy, substantially as shown.
